UNITED STATES PATENT OFFICE.

CHARLES F. CLARKE, OF HIGHLANDS, DELAWARE.

DESIGN FOR A TOY BANK.

SPECIFICATION forming part of Design No. 26,197, dated October 20, 1896.

Application filed September 11, 1896. Serial No. 605,536. Term of patent 7 years.

To all whom it may concern:

Be it known that I, CHARLES F. CLARKE, a citizen of the United States, residing at Highlands, in the county of New Castle and State 5 of Delaware, have invented and produced a new and original Design for a Combined Game and Toy Bank, of which the following is a specification, reference being had to the accompanying drawings, showing a part 10 thereof.

My invention consists of a new and improved design for a combined game and toy bank.

Figures 1 to 3, inclusive, are elevations of 15 different sides of my bank. Fig. 4 is a central vertical section through the same.

The design is in general shape that of a hollow truncated cone 1, and has a winding spiral path 2 in the form of a ledge extending about 20 the same from base to top. The said top is made slightly concave, as at 3, with an aperture 4 communicating with the interior of the cone. Along the course of the path 2 from bottom to top are placed a number of emblematic figures which are molded in the surface of the bank or built out from the same. 25 These figures and emblems represent incidents narrated in the tale of the *Pilgrim's Progress*. Just above the starting-point at 30 the bottom of the path 2 is an emblematic representation 4 of a ruined city. A little

farther up the path at the point 5 are a series of sockets or recesses 6, representing the slough of despond. Farther on up the path at 7 is a gate built over the same. Beyond this at 8 35 is a cross extending out partially over the path and making the same narrower at this point, and still farther on at 9 is a steep incline in the path. Beyond this inclination at 10 is a representation 11 of an inn or resting-house, with a slight depression or cavity 12 in the path in front of the same. Still farther on up the path is a representation 13 of a castle. This extends out over the path, leaving a narrow passage-way by the same. 45 Supporting-legs 14 14 are formed on the bottom of the truncated cone. The bottom of the cone is formed with a series of apertures 15 15.

Having thus described my invention, what 50 I claim as new, and desire to secure by Letters Patent, is—

The design for a combined game and toy bank, substantially as shown and described.

In testimony whereof I have signed this 55 specification in the presence of two subscribing witnesses.

CHARLES F. CLARKE.
